UNITED STATES PATENT OFFICE.

HIRAM HARRY HIRSCH, OF PHILADELPHIA, PENNSYLVANIA.

PORTABLE ELECTRIC-LIGHTING APPARATUS.

1,121,248.

Specification of Letters Patent.

Patented Dec. 15, 1914.

Application filed March 3, 1913. Serial No. 751,836.

To all whom it may concern:

Be it known that I, HIRAM H. HIRSCH, a citizen of the United States, residing at Philadelphia, in the State of Pennsylvania, have invented a certain new and useful Improvement in Portable Electric-Lighting Apparatus, whereof the following is a specification, reference being had to the accompanying drawings.

10 My invention relates to apparatus including an incandescent lamp in coöperative relation with a storage battery provided with means to attach it to the person of a miner or other operator, and provides a safety casing for the lamp designed to prevent ignition of fire-damp or other explosive gases when said lamp is broken.

As hereinafter described my invention includes a lamp casing and removable cover 20 provided with a transparent lens or panel, normally assembled in substantially hermetically sealed relation; said casing having distinct oppositely polarized elements included in the electric circuit by which the 25 lamp is energized, so constructed, and arranged that they are displaced and separated and thus break the circuit of the lamp, instantly extinguishing the latter, whenever said transparent element is broken or removed, and whenever said casing is crushed 30 or punctured.

My invention includes the various novel features of construction and arrangement hereinafter more definitely specified.

35 In the drawings:—Figure I is a vertical sectional view of a lamp casing conveniently embodying my invention and indicating its operative connection with a storage battery. Fig. II is a fragmentary front view of said 40 casing with the cover removed. Fig. III is a fragmentary front view of said casing, similar to Fig. II but showing said polarized elements relatively displaced and separated by crushing the casing. Fig. IV is a 45 fragmentary sectional view similar to Fig. I but showing the casing elements displaced and the lamp circuit broken by removal of the transparent panel. Fig. V is a vertical sectional view of a lamp casing, similar to Fig. I, but showing a modified form of my invention. Fig. VI is a fragmentary front view of the casing shown in Fig. V, but with the front cover removed. Fig. VII is a 50 fragmentary sectional view similar to Fig. V but showing the casing elements displaced and the lamp circuit broken by crushing the

casing local to the spring terminals thereof. Fig. VIII is a fragmentary sectional view similar to Fig. V but showing the casing elements displaced and the lamp circuit broken 60 by crushing the casing remote from said spring terminals. Fig. IX is a fragmentary sectional view similar to Fig. V but showing the lamp circuit broken by displacement of the transparent portions of 65 the casing.

Referring to the form of my invention shown in Figs. I to IV inclusive; the lamp casing includes the outer metallic shell 1 having the screw thread 2 to detachably engage the cover 3, and having the socket of insulating material 4 supporting the inner metallic shell 5 provided with the screw thread 6 to receive the incandescent electric lamp 7; said shell 5 serving as a reflector 70 for said lamp. Said shell 5 makes electrical contact with the metallic sleeve terminal 8 of said lamp which has the other metallic terminal 9 in electrical contact with the socket terminal 10.

Said inner shell 5 is insulated from the outer shell 1 by the annular bands 11 and 12, the latter extending between the shoulders 13 and 14 respectively upon said inner and outer shells and bracing them in spaced relation; the outer edges of said casing shells 1 and 5 and insulating band 11 forming a seat for the gasket 16 which is preferably of resilient material, so that the transparent lens or panel 18 is secured in substantially 90 hermetical relation with said casing when the latter is assembled as indicated in Fig. I.

As indicated, said outer shell 1 and inner shell 5 are electrically polarized by suitable connection with the storage battery 19, and 95 said shell 5 also supports the swing 20 which is electrically connected therewith and extends between said outer shell 1 and inner shell 5 and has its free end projecting through the notch 21 in said inner shell so 100 that it is normally upheld from the latter by the transparent panel 23, formed of glass or other frangible material.

Said outer shell 1 is corrugated to form a spiral seat 24 for the spring 25 which has 105 its outer end secured in the opening 26 in said shell and its inner end normally resting upon said spring 20 in electrical connection therewith; so that said casing elements 20 and 25 are respectively oppositely 110 electrically polarized in connection with said battery 19 and included in the circuit

by which said lamp 7 is energized. Said shell 5 is held in said socket 4 and mechanically connected by the screw 27 which is inflated therefrom but electrically connected 5 with said spring 10; the insulating material 28 being interposed between said shell and spring.

It is to be understood that both the metallic and transparent elements of said casing 10 are crushable, so that when either portion of said casing is crushed the lamp 7 is extinguished, by displacement of said oppositely polarized elements before it is possible for any incandescent portion thereof to ignite 15 fire-damp or other inflammable gases from the atmosphere surrounding said casing. For instance, as shown in Fig. III the outer shell 1 has been crushed so as to displace the spring 25 from the spring 20 20 and thus break the lamp circuit, and extinguish the lamp 7. As indicated in Fig. IV the panels 18 and 23 have been crushed and displaced so as to permit said spring 20 to separate from said spring 25 and thus break 25 the lamp circuit.

Referring to the form of my invention shown in Figs. V to IX inclusive; the lamp casing includes the outer metallic shell 31 having the screw thread 32 to detachably 30 engage the cover 33 and having the socket of insulating material 34 supporting the inner metallic shell 35 having the screw thread 36 to receive the incandescent electric lamp 37; said shell 35 serving as a reflector for said lamp. Said shell 35 makes electrical contact with the metallic sleeve terminal 38 of said lamp which has the other metallic terminal 39 in electrical contact with the socket terminal 40.

40 Said inner shell 35 is insulated from the outer shell 31 by the annular bands 41 and 42, the latter extending between the shoulders 43 and 44, respectively upon said inner and outer shells and bracing them in spaced 45 relation. The outer edges of said casing shells 31 and 35 and said insulating band 41 form a seat for the gasket 46 which is preferably of resilient material, so that the transparent lens or panel 48 is secured in 50 substantially hermetical relation with said casing when the latter is assembled as indicated in Fig. V.

As indicated, said outer shell 31 and inner shell 35 are oppositely electrically polarized 55 by suitable connection with the storage battery 49, and said shell 35 supports the spring 50 which is electrically connected therewith and extends between said outer shell 31 and inner shell 35 and has its free 60 end projecting through the notch 51 in said inner shell so that it is normally upheld from the latter by the transparent panel 53 formed of glass or other frangible material. Said shell 35 is held in said socket 34 and 65 mechanically connected by the screw 54

which is insulated therefrom but electrically connected with the spring 40.

Said outer shell 31 is electrically connected with the spring 55 which has its outer end secured in the opening 56 in said shell 70 and its inner end normally resting upon said spring 50 in electrical connection therewith; so that said casing elements 50 and 55 are respectively oppositely electrically polarized in connection with said battery 49 75 and included in the circuit by which said lamp 37 is energized. However, said outer shell 31 is provided with the resilient metal zone 57, normally retained therein by the indentation 58, shown in Fig. V, the diametrically opposite portion of said zone 57 serving as a fulcrum for the free end of said spring terminal 55, whereby the latter may be displaced and thus separated from the spring terminal 50 when the casing is subjected to crushing stresses. For instance, as shown in Fig. VII the outer shell 31 has been crushed and displaced toward the inner shell 35 so as to separate the spring 55 from the spring 50, although the fulcrum 57 of 90 the latter has not been shifted; the crushing effect being local to said spring contacts. On the other hand, crushing stresses upon said casing remote from said spring contacts displace said zone 57 so that the fulcrum portion thereof is displaced outwardly, as indicated in Fig. VIII, thus separating 95 said spring contacts 50 and 55 and breaking the lamp circuit. As indicated in Fig. IX the panels 48 and 53 have been crushed and 100 displaced so as to permit said spring 50 to separate from said spring 55 and thus break the lamp circuit and extinguish the lamp 37.

I do not desire to limit myself to the precise details of construction and arrangement 105 herein set forth, as it is obvious that various modifications may be made therein without departing from the essential features of my invention as defined in the appended claims.

I claim:—

1. An electric lamp casing having outer and inner metallic shells, included in the lamp circuit; means normally maintaining said shells in contact but causing separation thereof when said outer shell is crushed; whereby said circuit is broken when said casing is subjected to stresses tending to break the lamp.

2. An electric lamp casing having outer and inner metallic shells, means normally 120 maintaining said shells electrically connected but causing separation thereof when said outer shell is crushed; whereby said circuit is broken when said casing is subjected to stresses tending to break the lamp.

3. The combination with an electric lamp; of a casing for said lamp including an inner metallic shell serving as a reflector for said lamp; an outer metallic shell; means where- 125 by said shells are normally electrically con- 130

nected; and means whereby said shells are electrically disconnected when said casing is subjected to crushing stress.

4. The combination with an electric lamp; of a casing for said lamp including an inner metallic shell; an outer metallic shell; means whereby said shells are normally connected; and means whereby said shells are electrically disconnected when said casing is subjected to crushing stress.

5. In a lamp casing; the combination with a metallic shell; of a normally stationary but movable element in the lamp circuit;

means distinct from said element and from said shell, movable relatively to said shell 15 when the latter is deformed; whereby when said shell is deformed said element is shifted to break the lamp circuit.

In testimony whereof, I have hereunto signed my name at Philadelphia, Pennsylvania, this twenty-eighth day of February, 1913.

HIRAM HARRY HIRSCH.
